US00D695038S

(12) **United States Design Patent**
Metcalf et al.

(10) **Patent No.:** **US D695,038 S**
(45) **Date of Patent:** **** Dec. 10, 2013**

(54) **LOUNGE**

(75) Inventors: **Keith E. Metcalf**, Jasper, IN (US);
Ralph L. Langen, Santa Claus, IN (US);
Jeffrey P. Bueltel, Huntingburg, IN (US);
Todd E. Boyd, Jasper, IN (US);
Stanley J. Epple, Jasper, IN (US)

(73) Assignee: **Kimball International, Inc.**, Jasper, IN (US)

(**) Term: **14 Years**

(21) Appl. No.: **29/408,765**

(22) Filed: **Dec. 16, 2011**

(51) LOC (9) Cl. **06-01**

(52) U.S. Cl.

USPC **D6/381**

(58) **Field of Classification Search**

USPC D6/334-338, 349, 355, 361, 368-370,
D6/376, 379-381, 708, 716, 716.1;
297/16.1, 42, 94, 135, 175, 232, 233,
297/350, 351, 445.1, 448.1, 448.2, 451.9;
5/12.1, 12.2

See application file for complete search history.

(57) **CLAIM**

The ornamental design for a lounge, as shown and described.

DESCRIPTION

FIG. 1 is a front perspective view of a lounge according to our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The break lines in the center of FIGS. 1-3 and 6 denote varying width, and form no part of the claimed design.

1 Claim, 5 Drawing Sheets
